Primary Examiner — Erich G Herbermann*Assistant Examiner* — Liv C Anderson(74) *Attorney, Agent, or Firm* — Banner & Witcoff, Ltd.(57) **CLAIM**

The ornamental design for a color changeable light as shown and described.

DESCRIPTION

FIG. 1 is a front top perspective view of a color changeable light showing our new design;

FIG. 2 is a rear bottom perspective view thereof;

FIG. 3 is a top view thereof;

FIG. 4 is a bottom view thereof;

FIG. 5 is a left side view thereof;

FIG. 6 is a right side view thereof;

FIG. 7 is a front view thereof; and,

FIG. 8 is a rear view thereof.

The broken lines depict portions of the color changeable light that form no part of the claimed design.
